CLAIM

The ornamental design for a scope mount, as shown and described.

DESCRIPTION

FIG. 1 is a perspective view of a scope mount according to the present application, the scope mount being shown rotated 90 degrees to the right.

FIG. 2 is a rear view of the scope mount of FIG. 1.

FIG. 3 is a front view of the scope mount of FIG. 1.

FIG. 4 is a top side view of the scope mount of FIG. 1.

FIG. 5 is a bottom view of the scope mount of FIG. 1.

FIG. 6 is a left side view of the scope mount of FIG. 1; and, FIG. 7 is a right side view of the scope mount of FIG. 1. The surface shading lines on the claimed portion are provided only to indicate the character and/or any contour or curvature of the surfaces, and do not indicate color, texture, markings that actually exist thereon, indicia, graphic representations, surface treatment, or any other ornamentation applied to the article.
